US00D454404S

(12) United States Design Patent (10) Patent No.: US D454,404 S
Merrick (45) Date of Patent: * Mar. 12, 2002

(54) CENTURY FENCE POST FINIAL
(75) Inventor: Richard James Merrick, Alda, NE (US)
(73) Assignee: T.M.C., Inc., Alda, NE (US)
() Term: 14 Years
(21) Appl. No.: 29/116,402
(22) Filed: Jan. 3, 2000
(51) LOC (7) Cl. 25-01
(52) U.S. Cl. D25/135
(58) Field of Search D25/135, 38; 256/65, 256/66; 52/300, 301

(57) CLAIM

The ornamental design for a century fence post finial, as shown and described.

DESCRIPTION

FIG. 1 is a front perspective view showing the century fence post finial of the present invention.

FIG. 2 is a top plan view showing the century fence post finial of the present invention.

FIG. 3 is a bottom plan view thereof.

FIG. 4 is a front elevational view thereof; and,

FIG. 5 is a side elevational view thereof.

1 Claim, 4 Drawing Sheets
